UNITED STATES PATENT OFFICE.

ANKER S. LYHNE, OF BRIDGEPORT, CONNECTICUT.

VANITY BOX.

Application filed April 15, 1925. Serial No. 23,199.

This invention relates to vanity boxes, and has for an object to provide a box of this character which will be neat and attractive in appearance and easily carried in a lady's handbag, which will be simple in construction and may be manufactured at low cost, and especially to provide a box of this type in which there is provided a concealed compartment in which lip paste may be carried.

10 It is a still further object of the invention to provide a construction in which the lip paste is carried in a separate container which may be inserted as a whole in the box for renewal purposes, and in which the old container after the supply of paste has been ex-

15 hasted may be easily removed and renewed. The box also includes a sanitary closure for this container while in the box which will be swung to and from the closed position for

20 the container when the compartment for the container is closed or opened.

With the foregoing and other objects in view, I have devised the construction illustrated in the accompanying drawing forming a part of this specification, similar reference characters being employed throughout the various figures to indicate corresponding elements. In this drawing,

Fig. 1 is a top plan view of the vanity box 25 closed.

Fig. 2 is a side elevation of the box open and with the container for the lip paste also open.

Fig. 3 is a transverse section through the 30 box on an enlarged scale, the section being substantially on line 3—3 of Fig. 1.

Fig. 4 is a similar section of the upper part of the box taken substantially on line 4—4 of Fig. 1, the rouge paste container being shown 35 in elevation.

Fig. 5 is a top plan view of the box in open position on an enlarged scale.

Fig. 6 is a top plan view of the container for the rouge paste illustrating how it may 40 be furnished on the market, and

Fig. 7 is a side elevation thereof.

My improved box includes hinged cover and body sections 10 and 11 respectively, the hinged connection between the sections being 45 shown at 12. These sections are preferably made of sheet metal and their top and bottom walls are preferably concavo-convex, as indicated to give a neat and attractive appearance to the box and also to give a greater capacity to the box. The meeting edges of

the cover and body sections are formed telescoping to give a tighter closure. For this purpose the upper portion 13 of the side walls of the body section is reduced in diameter to fit within the open side of the 60 cover section, as shown in Fig. 3, so that the exposed portions of the side walls of the cover and body sections are of substantially the same diameter to give a practically continuous surface to the box when closed. The 65 sections are held in closed position by a suitable catch, such as a lip 14, projecting from the body section to engage a shoulder 15 formed in the cover section by cutting the side wall thereof and forcing a portion of 70 the wall outwardly.

Mounted in one of the sections, preferably the lower or body section 11, is a compact 16 of any suitable type of powder and there is provided a puff 17 for use in applying the 75 same. In the other section, in the present case the cover section 10, is an insert 18 preferably in the form of a metal ring having a bead or flange 19 in its side wall to frictionally engage the inner surface of the side 80 walls of the cover section to retain this insert in the section. It is provided in one side thereof with spaced slits 20 forming a spring tongue or clip 21, and this clip is provided with an inwardly extending lug 22. 85

The insert is provided on the opposite side thereof with a corresponding lug 23. These lugs are used to removably secure in this section of the box an open container 24 carrying a lip paste, such as rouge paste 25, and 90 in order that the container may be securely held by these lugs it is recessed in the side wall thereof, preferably by providing a continuous annular groove 26 about the container, as this continuous groove allows the 95

100 container to be inserted in any position. It will be apparent that as the container is inserted the spring clip or tongue 21 will yield and allow the lugs 22 and 23 to pass over the enlarged portion of the container and into 105

the groove 26. The container will thus be 110 securely retained in the cover section of the box, but it may be easily removed at any time for the insertion of a filled container and renewal of the paste supply after the old supply has been exhausted.

The compartment in which the rouge paste 115 container is mounted is closed by means of a holder 27 hinged to the ring or insert 18 by means of a hinge 28. This holder prefer-

120

125

135

ably comprises a sheet metal member having a flange on one side thereof in which a mirror 29 is mounted by a ring 30. On its opposite side or back is mounted a closure 31 for the open container 24. This closure, in order to make a neat and sanitary construction, is preferably a flat plate of some material which is not corroded or chemically affected by the paste within the container, 10 such as aluminum. It is preferably secured to the back of the holder by means of ears 32 cut and bent backwardly from the back of the holder and passing through openings in the closure and then folded over on the 15 surface thereof, as indicated in Figs. 3 and 5. At the opposite end from the hinge 28, the holder or flange 27 is provided with a ring or other suitable means 33 for swinging the holder on its hinge to give access to the 20 compartment in which the rouge paste container is mounted. The holder 27 fits tightly within the insert or ring 18 to form a tight closure therefor and also to retain the holder in the closed position when the box is open. 25 By this arrangement when the box is opened the compartment containing the rouge paste is not exposed, but the powder compact 18 and puff 17 together with the mirror only are exposed. If however, the user desires 30 to use the rouge paste it is easily accessible by lifting the holder 27 by means of the ring 33.

It will be apparent that as the closure 31 for the container 24 is mounted on the back 35 of the holder 27 the operation of opening this compartment also removes the closure from the rouge paste container, and this paste is, therefore, exposed for use. Also, for the same reasons, when the mirror holder 27 is 40 forced back to its original position to close the compartment in the cover section, the closure plate 31 is forced tightly against the open side edge of the container 24 and tightly seals the same.

45 The container 24 is preferably of aluminum or other suitable material which will not be affected by the paste, and will be purchased on the market complete, as indicated in Figs. 6 and 7, filled with the paste. 50 It is closed by a cover 34 and sealed by means of a strip of paper or other suitable material 35 pasted around the edges, as indicated, and of course any markings as grade marks, trade-marks and so forth may be 55 printed on this paper. When the user wishes to renew the supply of rouge paste in the box all that is necessary is to break the paper seal, remove the cover 34 and then insert the container holding the paste in 60 the vanity box as above described.

65 This construction of box provides an ample supply of white or flesh colored powder for ordinary use, but there is always provided also the lip paste in the sealed compartment where it is easily accessible. This

is a more convenient and more satisfactory form of lip paste than that of the usual lip stick, and usually the paste in this form may be secured in a better quality, and it also is provided in just the right consistency for 70 application. The closure 31 tightly closes the container while in the case so that it is perfectly sanitary at all times, and as this closure is a plain flat disc it is easily cleaned. 75

Having thus set forth the nature of my invention, what I claim is:

1. In a vanity box, hinged body and cover sections, a metal ring in one of the sections having a yieldable portion and inwardly 80 projecting lugs one of which is on said yieldable portion, an open container provided with a depression in its side wall to receive the lugs to removably retain the container in the box, and a separate closure for the 85 container hinged to the box.

2. In a vanity box, hinged body and cover sections, an open container, means in one of the sections for removably securing the container, and a separate closure for the 90 container hinged to the box, said container being removable from the section independently of the closure.

3. In a vanity box, hinged body and cover sections, a metal ring in one of the sections, 95 an open container, coating means on the ring and container for removably securing the container in the box, and a closure for the container hinged to the ring.

4. In a vanity box, hinged body and cover 100 sections, a metal insert in one of the sections provided with a spring clip, a container having a groove in its side wall, and lugs on the insert projecting into said groove to retain the container in the box, one of the lugs 105 being on the spring clip, and a separate closure for the container hinged to the insert.

5. In a vanity box, hinged body and cover sections, a metal insert in one of the sections provided with a spring clip, a container 110 having a groove in its side wall, said insert being provided with lugs projecting into the groove to retain the container in the box, one of the lugs being on the spring clip, and a separate closure for the container hinged 115 in the box independently of the container.

6. In a vanity box, hinged cover and body sections, an open container, means mounted in one of the sections for removably securing the container therein, a holder hinged in the 120 box independently of the container, a mirror mounted in the holder and exposed on one side thereof, and a closure for the container on the other side of the holder.

7. In a vanity box, hinged body and cover 125 sections, an insert mounted in one of the sections, an open container, said insert being provided with means for removably securing the container in said section, a holder hinged to the insert, a mirror mounted in the holder 130

and exposed at one side thereof, and a closure for the container secured to the other side of the holder.

8. In a vanity box, hinged body and cover sections, an insert mounted in one of the sections, an open container, said insert being provided with means for removably securing the container in said section, a metal holder hinged to the insert, a mirror mounted

in the holder and exposed on one side thereof, said holder being provided with ears projecting from the other side thereof, and a closure plate for the container secured to the back of the holder by said ears. 10

In testimony whereof I affix my signature. 15

ANKER S. LYHNE.
